UNITED STATES PATENT OFFICE.

WALTER E. PRATT, OF RENO, NEVADA.

AUTOGRAPHIC REGISTER.

Application filed March 12, 1924. Serial No. 698,762.

The present invention relates to new and useful improvements in autographic registers, and it pertains more particularly to new and improved mechanism for holding and for facilitating the feeding of paper.

With the above and other objects in view, reference is had to the accompanying drawings, in which—

Figure 1 is a top plan view of a device 10 constructed in accordance with the present invention;

Fig. 2 is a view in side elevation thereof;

Fig. 3 is a detail sectional view thereof;

Fig. 4 is a top plan view of a slightly 15 modified form of the invention, and

Fig. 5 is a top plan detail view of a still further modified form of the invention.

Referring more particularly to the drawings, the reference numeral 10 designates the 20 body or housing of the autographic register, and 11 designates the top wall or plate thereof. The top wall or plate 11 is provided, adjacent one end thereof, with a cut-out portion 12, to provide a writing space.

25 Mounted within the housing and carried by shafts A, are rolls of paper B, and the paper of said rolls is adapted to be fed over idle rollers 14, as shown in dotted lines in Fig. 2.

As more clearly shown in Fig. 3, there is a 30 bottom plate 15, which is spaced with respect to the top wall 11, and the paper is fed in the space between the top wall or plate 11 and the plate 15. The plate 11 is provided near its forward end with a cut-out portion 16, and such cut-out portion 35 permits of the several sheets of paper being gripped to pull or feed them through the machine, which operation is illustrated in Fig. 3.

40 The extreme forward end of the top plate or wall 11 is beveled as shown at 17, to provide a cutting edge 18, by means of which the several strips of paper are separated into individual leaves or the like.

45 Extending transversely of the housing 10 of the machine, there is a rock shaft 20, and projecting forwardly from said rock shaft and carried thereby are two spaced arms 21. As more clearly shown in Fig. 3, each 50 of these arms has an angular end portion 22, which angular end portions are adapted to move upwardly through openings 23 in the top wall or plate 11, such openings 23 being positioned upon opposite sides of the opening 16 heretofore mentioned. One 55 end of the shaft 20 is projected beyond the

body or housing 10, as shown at 25, and secured to such extended end there is a lever 26, which serves as an operating member by means of which the shaft 20 is rocked 60 for a purpose to be hereinafter described.

In Fig. 4 of the drawings a slightly modified form of the invention is shown, and in this figure the opening 30 (designated as "16" in the preferred form of the invention) is provided with angularly-disposed side walls 31, a curved front wall 32, and a straight rear wall 33, the straight rear wall 33 being connected to the angularly-disposed side walls 31 by straight side walls 70 34.

In that form of the invention shown in Fig. 5, the opening is designated by the reference numeral 40, and such opening is 75 of rectangular form as shown.

In each of the modified forms of the invention, the end of the top wall 11 is provided with a cutter 18 heretofore described.

The device operates in the following manner:

With the parts in the position shown in Fig. 2, when it is desired to feed the paper strips, the lever 26 is elevated to rock the shaft 20, and cause the angular ends 22 of the arms 21 to disengage the openings 23. 85 It is to be understood that when the angular ends 22 engage the openings 23, they pass through openings in the strips of paper and thus hold the strips of paper against movement. When, however, the angular ends 22 have been disengaged from the openings 23 and the openings in the strips of paper, the strips are free to be fed forwardly and pulled by the hand of the operator as shown 90 in Fig. 3. Immediately the strips are started the lever 26 is dropped which rocks the shaft 20 to a position where the angular ends 22 of the arms 21 will engage the under face of the bottom strip of paper, and immediately the holes in the paper register 95 with the angularly disposed ends 22 of the arms 21, said angularly-disposed ends pass therethrough and prevent further movement of the strips of paper. When the operator has fed the strips of paper sufficiently to 100 bring about this result, he tears off the strips along the cutter 18.

While in the present instance the lever 26 is shown upon that end of the shaft which would be positioned upon the right-hand side of the machine, it is obvious that the shaft may be extended upon the other side 110

of the machine and the lever positioned thereon, which may be desirable in some instances, and, therefore, I do not wish to be limited to the exact showing of this element in the accompanying drawings.

What is claimed is:

1. In an autograph register, a top plate having a cut-out portion forming a writing space, an opening adjacent its forward edge 10 to provide for gripping the sheets to pull them through the register and a small opening at each side of the last named opening, the forward edge of the plate being beveled to form a cutting edge, a plate of less length than the top plate and arranged below and spaced therefrom to form a guide for the sheets, a rock shaft below the top plate and having arms with angular ends adapted to

enter the small openings of said plate, and an operating lever on the shaft and normally holding the arms of the shaft in engagement with said openings.

2. In an autograph register, a housing having an opening at one end through which the sheets are adapted to be pulled by being gripped by the operator and provided in its top with oppositely arranged and spaced openings, a shaft mounted in the housing below the top and having arms thereon, said arms having angular ends adapted to enter the openings in the top of the housing, and a lever on one end of the shaft and normally holding the arms of the shaft projecting into the said openings.

WALTER E. PRATT.
